UNITED STATES PATENT OFFICE.

NICHITU V. GHETIA, OF CLEVELAND, OHIO.

HAIR CLIPPER.

1,422,352.

Specification of Letters Patent. Patented July 11, 1922.

Application filed June 22, 1921. Serial No. 479,602.

To all whom it may concern:

Be it known that I, NICHITU V. GHETIA, a citizen of the United States, residing at Cleveland, in the county of Cuyahoga and State of Ohio, have invented certain new and useful Improvements in Hair Clippers, of which the following is a specification, reference being had to the accompanying drawings.

10 This invention relates to hair clippers, and one of the principal objects of the invention is to provide a portable outfit including a clipper which may be operated electrically through a source of power carried in the outfit or through an outside source, as is found most desirable, and which at the will of the operator may be converted into a manually operated clipper.

Clippers have heretofore been devised 20 which were adapted to be converted from electrically operated clippers to manually operated clippers, but the mechanism was so complicated that they were not effective for any length of time. It is therefore the 25 object of this invention to simplify the construction of these present clippers and to provide simple and efficient means whereby the clipper may be converted from a power operated clipper to a manually operated one.

30 A further object of the invention is the provision of novel means for mounting a manual operating handle in such manner that it may be utilized to operate an electrical switch when thrown out of manual 35 operating position and will lie out of the path of the switch when in manual operating position.

Further objects of the invention will appear as the following specific description is 40 read in connection with the accompanying drawings which form a part of this application and in which:

45 Figure 1 is a top plan view of a clipper outfit with the cover removed so as to show the relative position of the parts therein;

Figure 2 is a top plan view of the clipper showing parts arranged for power operation;

50 Figure 3 is a similar view showing the parts arranged for manual operation;

Figure 4 is a perspective view of the manual operating lever removed;

55 Figure 5 is a section taken on the line 5-5 of Fig. 3;

Figure 6 is a section taken on the line 6-6 of Fig. 3;

Figure 7 is a perspective view of the lever mounting pin.

Referring more particularly to the drawings, 1 represents a stationary cutter plate 60 which has connected to the same and extending rearwardly therefrom a casing plate 2 provided with laterally extending flanges 3 and 4 which are engaged by the cover 5 when in position. This plate 2 and its associated flanges and top are preferably made of some non-magnetic material, and mounted upon, and insulated from the flange 3 by means of the strip of insulation 6, are the electro-magnets 7 arranged for actuation of 70 the power operating lever 8 to be herein-after described.

Mounted upon the stationary cutter plate 1 is a removable cutter plate 9 having slots 10 to receive the headed guide pins 11 which 75 guide the reciprocation of the plate as is understood. The movable plate 9 is provided with a centrally arranged notch 12 which is engaged by the forward extension 13 of the operating lever, and which forward extension is normally held in one position by a helical-spring 14 secured to the plate 1. The operating lever is mounted upon a pivot pin 15 arising from the plate 2, which pin, as is shown in Figure 7, is provided with a head 16 and a rounded shank 17. Intermediate the shank 17 and the head 16 the pin is reduced on diametrically opposite sides, as indicated at 18, and mounted upon the reduced portion is the manual 80 operating lever 19 provided with an elongated 8-shaped or double keyhole slot 20 which when engaged with the underside of the head 16 will freely rotate on the pin when the pin is in either of the enlarged 95 ends of the slot. The lever can be shifted upon the pin by turning the lever to such position that the parallel sides of the reduced portion are arranged parallel with the longitudinal axis of the slot. When the 100 parallel sides of the reduced portion are at right angles to the longitudinal axis of the slot, the lever cannot be shifted upon the pin, as will be readily understood. The forward end of the lever is provided with a 105 yoke 21 which in certain positions of the lever is arranged to engage a stud 22 projecting vertically from the forward end 13 of the operating lever, while the rear end of the lever 19 is formed to provide a handle 110 23 lying substantially parallel to the flange or stationary handle 8.

In the casing outfit which has been indicated at 24, I preferably provide a source of current in the form of a storage or dry battery 25, one terminal of which may be connected by a cord to one terminal of the electro-magnets, as at 26, and the opposite terminal may be connected to one terminal of the make and break connections, as shown at 27. The terminals of the battery may also be connected and I may connect two of the terminals of the transformer T to the terminals 26 and 27. This transformer is preferably an ordinary bell transformer whose opposite terminals may be connected to 110-volt circuit such as is used in house lighting, and the machine is preferably operated through this source of power and the battery only used where such power is not available.

Intermediate the terminal 27 and the one contact 28 of the make and break contacts, I provide a switch 29 in the form of a spring retracted plug, as shown in Figures 2 and 3, which when the machine is arranged to be operated electrically, lies in the path of the rear end 23 of the lever 19, so that upon moving the handle toward the stationary handle 3 the plug switch will be operated to complete the circuit from the terminal 27 to the make and break contact 28. The opposite make and break contact 30 is preferably grounded upon the plate 2 as is also the last one of the magnets which are wired in series.

In the electrical operation of the clippers the spring 14 holds the rear end of the operating lever 8 against the contacts 28 and 30 so that when the manual operating lever is moved toward the stationary handle 3, the switch 29 completes the circuit as follows: terminal 27, switch 29, contact 28, lever 8 to contact 30, over the plate 2 to the electro-magnets and from there over conduit 31 to terminal 26 and back to the battery or transformer. The circuit being thus completed and the magnets energized, the lever 8 forming the armature thereof is drawn toward the magnets against the tension of the spring 14. Immediately upon the lever being released from the contacts 28 and 30, the circuit is broken, and the magnets deenergized, permitting the spring to again return the armature to a point where it bridges the contacts 28 and 30, as will be readily understood. As long as the switch 29 is held to complete the circuit from the terminal 27 to the contact 28, this reciprocation of the armature and the making and breaking of the circuit will continue and thus throw the forward end 13 of the lever reciprocating the cutter 9 over the cutter plate 1.

When it is desired to manually manipulate the clipper the lever 19 is turned upon the pivot pin 15 until the parallel sides of the reduced portion of the pin are parallel

with the longitudinal axis of the slot 20 when the lever can be moved forward and the pin engaged in the rearmost enlargement of the slot, as is common in adjustable pliers. When this has been done and the lever operated to carry the handle 23 toward the stationary handle 3, it will be seen that the rear end of the handle 23 is slightly forward of the switch 29 and the switch out of the path of the handle and also that the yoke 21 is in position to engage the stud 22. By moving the handle 23 toward the stationary handle 3, the lever 8 is operated similar to the action of the magnets, and by gripping and releasing the handles 23 and 3 the cutter plate 9 may be caused to reciprocate in a similar manner to the power reciprocation just described.

I have described the magnets as being wired in series but I wish it to be clearly understood that they may be wired in parallel or they may be of varying voltage capacities and one or more of them used with the battery, while the remainder may be wired simply for use with the transformer, or the wiring may be independent of one of the magnets or any of them from the transformer and battery.

What I claim is:—

1. A clipper comprising relatively movable cutter plates, power operated means for producing relative movement of the plates embodying in part an operating lever, a shiftable manually operated member, and means for operatively connecting the same to the operating lever.

2. A clipper comprising relatively movable cutter plates, power operated means for producing relative movement of the plates embodying in part an operating lever, and a manually operated member having a shiftable engagement with a pivot for engaging a part of the operating lever to operate the same.

3. A clipper comprising relatively movable cutter plates, power operating plates for producing relative movement including an electrical switch, an operating lever and a manually operated member having a shiftable engagement with a pivot whereby it may be selectively engaged with a part on the operating lever or with the switch.

4. A clipper comprising relatively movable cutter plates, electrically controlled operating means for producing relative movement of the plates, embodying in part a pivoted operating lever and an electrical switch, and a manually operated member pivoted and shiftable on the pivot of the operating lever whereby it may be selectively engaged with a part on the operating lever or the electrical switch.

5. A clipper comprising relatively movable cutter plates, power operated means for producing relative movement of the plates

including in part electrically operated magnets, an electrical switch and an operating lever, said operating lever being pivoted and spring-pressed in one direction, and a manually operated member pivoted and shiftable on the pivot of the lever whereby it is adapted for selective engagement with a part on the lever or with the switch, said manually operated member adapted to move 5 the lever against the tension of the spring to produce relative movement of the plates.

6. In a clipper, a fixed cutter plate, a movable cutter plate, a stationary handle, a pivoted lever for reciprocating the movable 10 cutter plate over the stationary cutter plate, electrical means including a switch for reciprocating said lever, a stud on the lever and a manually operated handle movable 15 toward and away from the stationary handle and pivoted and shiftable on the pivot of the operating lever whereby it is arranged 20

for selective engagement with the stud or the switch.

7. A clipper comprising relatively movable cutter plates, normally inoperative 25 power operated means for producing relative movement of the plates, and a manually operated lever shiftable for operative connection with the plates or for rendering said power operated means operative. 30

8. A clipper comprising relatively movable cutter plates, an operating lever for producing relative movement of the plates, power operated means associated with the operating lever and normally inoperative, 35 and manual operating means shiftable to actuate the operating lever or to render the power operated means operative.

In testimony whereof I hereunto affix my signature.

NICHITU V. GHETIA.
